UNITED STATES PATENT OFFICE.

LEVI SHERMAN SKELTON, OF OKMULGEE, OKLAHOMA.

GLASS-POT DEVICE.

1,178,543.

Specification of Letters Patent. Patented Apr. 11, 1916.

Application filed May 3, 1913. Serial No. 765,326.

To all whom it may concern:

Be it known that I, LEVI SHERMAN SKELTON, a citizen of the United States, residing at Okmulgee, in the county of Okmulgee

and State of Oklahoma, have invented certain new and useful Improvements in Glass-Pot Devices, of which the following is a specification, reference being had therein to the accompanying drawing.

This invention provides a glass-pot-carrying frame, pivotally mounted in such manner that one of a plurality of pots thereon can be brought to and held in upright position while glass is being drawn therefrom, and so arranged that pots may easily be secured on and removed therefrom. The device includes in association with each pot a hinge, whereby the pot that is inverted may be permitted to hang at an angle to the frame axis to facilitate cleaning or removal of refuse glass therefrom. Further, the arrangement is such that air may be supplied through the pot in use to the interior of the article being drawn therefrom and automatically shut off from the other pot on the frame.

Generally, it is an object of the invention to simplify the construction of such devices, to enhance the ease and reliability of operation, and to provide a pot-carrying device particularly adapted for use separate from a furnace.

When read in connection with the description herein, the details of construction and arrangement of parts contemplated by the invention will be apparent from the accompanying drawing, forming part hereof, wherein an embodiment of the invention is disclosed, for purposes of illustration.

While the embodiment shown and described herein now is considered a preferable one, it is to be understood that it is not the intention to be limited necessarily to the exact delineation herein in interpretation of claims hereinafter, as it is obvious that modifications of structure can be made within the limits prescribed by the claims without departing from the nature and spirit of the invention.

Like reference-characters refer to corresponding parts in the views of the drawing, of which—

Figure 1 is an elevation, partly in section; and Fig. 2 is a plan view.

Referring more particularly to the drawing, 3 designates standards supported in a

fixed position in any suitable manner. These standards carry substantially horizontal shafts 4 and 4' adjustably and removably held by set-screws 5 or the like.

Rotatably mounted on shafts 4 and 4' is a frame 6, preferably circular in plan. The frame is spaced from one of the standards by the collar 7 and an outwardly-extending hub 8 journaled on shaft 4. On the other side the frame has an outwardly-extending hub 9 journaled on shaft 4' and terminating in an enlargement 10 in which there is a beveled recess 11 on each side of the shaft, whereby there is formed a member of a clutch. Next on shaft 4' there is a member 12 (constituting the other member of the clutch) axially movable on the shaft and having a lug 13 arranged to seat in recess 11. Member 12 is prevented from turning on shaft 4' by a key 14. A coil-spring 15 is disposed between member 12 and a collar 16 fast on the shaft. The arrangement is such that, when the frame is turned on the shafts, the lug 13 will ride out of recess 11, and that, when the frame is turned one-half of a complete rotation, the lug under action of spring 15 again will seat in the recess, restrain the frame from rotative movement, and maintain it in fixed position until sufficient force to make the lug ride out of the recess again is applied to the frame. A turning member 17, adapted to be grasped by the hands, is fixed to one of the hubs.

The frame 6 has extending laterally therefrom flanges 18. Each flange is disposed on the opposite side of the frame from the other, and each lies in a single plane that is parallel, or substantially parallel, to the other flange. The flanges are arranged to have molten-glass pots 19 seat thereon. Each pot has extending around its exterior a heat-insulating covering of asbestos or other suitable material 20, which is held in place by a metallic band 21 surrounding the pot and secured by a ring 22, which overlaps the band 21. The ring is secured to the frame by a hinge 23 at one place on its periphery, this hinge including a pivot-rod 24 that may be withdrawn when it is desired to remove the pot entirely from the frame, and by bolts 25 passing through the flange 18 at other places on the periphery or by other suitable separable fastenings. When a pot is brought to an inverted position by turning the frame, the separable

fastenings may be removed and the pot permitted to swing downwardly on the hinge to an angular position with respect to the frame axis, as shown in dotted lines in Fig. 1, to facilitate removal of refuse glass or other matter therefrom.

For the purpose of supplying air to the interior of an article being drawn, each pot has extending upwardly of its glass-holding space a central boss 26, and a passage or duct 27 extends from the bottom of the pot through, and to the top of, the central boss. A pipe 28 extends from the plane of one flange 18 to the plane of the other, and it is so positioned that its ends will register with the passage 27 when the pots are in place and then form a tight connection with the bottom of the pots. Near each end of pipe 28 is a valve-chamber 29, within which is a gravity-valve 30. A central T-coupling 31 of pipe 28 between the two valves is journaled on the end of a supply-pipe 32, which is disposed axially of and fast in shaft 4 and extends outwardly thereof a sufficient distance for communication with any suitable source of air supply. The valves 30 are arranged so that the one that is above the coupling or adjacent to the upper pot from which glass is being drawn will be open and the one that is below the coupling or adjacent to the lower pot will be closed, whereby air entering through supply-pipe 32 will be discharged through the passage 27 of the upper pot and prevented from discharge from the passage of the lower pot. When the frame is turned over, the valve adjacent to the pot that was uppermost will close and that adjacent to the pot that was lowermost and now becomes the uppermost pot will open automatically, whereby flow of air will be directed properly without the necessity of attention on the part of the operator.

The shaft 4' may be adjusted on the supporting-standards by loosening and tightening set-screws 5, so that the upper pot always will be held in a substantially horizontal position when the lug 13 is seated in recess 11 of the clutch.

Having thus described my invention,

what I claim as new, and desire to secure by Letters Patent, is—

1. A glass-pot device comprising a frame rotatable about a substantially horizontal axis and having thereon a plurality of glass-pots each having a passage extending through the glass holding-space thereof, an air-supply pipe in communication with each of said passages, and a valve for each passage controlling admission of air thereto and arranged to open when the pot containing its passage is uppermost and to close when said pot is lowermost. 55

2. A glass-pot device comprising a frame rotatable about a substantially horizontal axis and having thereon two oppositely-disposed glass-pots each having a passage through the glass holding-space thereof, a pipe in communication with each of said passages, an air-supply conduit leading into 65 said pipe intermediate its ends, and in said pipe on each side of said conduit a valve arranged to open when it is above said conduit and to close when it is below said conduit. 70

3. A glass-pot device comprising a frame 75 rotatable about a substantially horizontal axis and having thereon two oppositely-disposed glass-pots each having a passage through the glass holding-space thereof, a pipe extending from one of said passages to 80 the other, a centrally-positioned coupling in said pipe, an air-supply conduit connected with said coupling, and in said pipe on each side of said coupling a valve arranged to open when it is above said coupling and to 85 close when it is below said coupling.

4. A glass-pot device, comprising a cylindrical frame rotatable about a horizontal axis, pots oppositely mounted on said frame, a metallic band around each pot and hinged- 90 ly connected to the frame, and means secured to the frame and engaging the bands to hold the pots in place.

In testimony whereof I affix my signature in presence of two witnesses.

L. SHERMAN SKELTON.
